UNITED STATES PATENT OFFICE.

HENRY E. RICHMOND, OF WESTWOOD, NEW JERSEY.

STEREOSCOPE.

No. 857,539.

Specification of Letters Patent.

Patented June 18, 1907.

Application filed March 30, 1906. Serial No. 308,843.

To all whom it may concern:

Be it known that I, HENRY E. RICHMOND, a citizen of the United States, and a resident of Westwood, in the county of Bergen and 5 State of New Jersey, have invented certain new and useful Improvements in Stereoscopes, of which the following is a specification.

My invention relates to means for adjustably securing the view holder of a stereoscope to the shaft thereof, and also means for keeping the view holder in true axial alinement on the shaft.

One of the objects of my invention is to 15 provide a cheap and efficient means for holding the view holder to the shaft and which may be easily released from its grip on the shaft to permit the view holder to be readily moved along the shaft to any desired position, and then when released, to hold the view holder firmly in said position.

Another object is to provide a guide or guides for holding the view holder in true axial alinement on the shaft.

25 Another object is to make this construction cheaply and out of as little material and with as little waste as possible.

Other objects will appear from the herein-after description.

30 The invention is illustrated in the accompanying drawing, which forms a part of this application, and in the different views of which the same reference character indicates the same part.

35 Referring to the drawing, Figure 1 is a side elevation of a stereoscope with the improvement applied thereto. Fig. 2 is a longitudinal sectional view showing the clamp released from its gripping position on the shaft.

40 Fig. 3 is an under side view showing the preferred construction of clamp and guide. Fig. 4 is a section on line 4 of Fig. 3. Fig. 5 is a perspective view of the alinement guide shown in Fig. 4. Fig. 6 is a construction

45 similar to that shown in Figs. 3 and 4, but with two alining guides, both of which are integral with the main portion of the clamp. Fig. 7 is a perspective view of a modification. Fig. 8 is a section on line 8 of Fig. 7. Fig. 9 is a perspective view of another modification.

The part marked A on the drawing represents a stereoscope of the ordinary construction. B is the shaft thereof and C the cross- 5 bar of the view holder. This cross-bar is

provided on its under side with a groove D into which fits the shaft B in the usual manner.

The part marked E represents the improved clamp which is struck up from sheet metal of the proper spring temper. The part lettered E' is the main plate of the clamp which spans the cut-out part of the cross-bar of the view holder through which the shaft passes, and is secured to the under side of the cross-bar by screws or nails passing through holes e in the ends thereof and into the cross-bar. Extending from each side of the main plate, and at right angles thereto, are two arms, the metal of which is cut through dividing each arm into two parts e¹ e². A corresponding part of each of these arms forms a leaf spring which bears against the under side of the shaft to hold the view holder in its set position on the shaft. The other corresponding parts are turned down to form finger pieces, which when pressed together, release the leaf springs from bearing on the shaft to permit the view holder to be moved longitudinally thereon.

In Figs. 7 and 8 I have shown the two parts lettered e² turned down to form the finger pieces, while in the other figures, I have shown the other parts e¹ turned down for this purpose.

50 In order to raise the leaf springs from engagement with the under side of the shaft when the finger pieces are pressed together, it is necessary to weaken the main portion E' of the clamp longitudinally thereof, so that a fulcrum for the leaf springs may be formed. This may be done in several ways. For example, the metal in this portion 1^e may be made thinner, as shown in Figs. 7 and 8, by drawing it out or removing a portion thereof, or the metal may be entirely removed, forming a slot 2^e therein, as shown in the other figures of the drawing.

55 When the clamp is constructed as described, the leaf springs will be readily released when the finger pieces are drawn together, the said leaf springs moving on a fulcrum at the weakened portion of the main part E' of the clamp.

In order to permit the view holder to be moved freely on the shaft, it is customary to make the cut-out portion in the cross-bar on which the shaft fits, of greater length than the width of the shaft. This causes the view holder to move out of axial alinement on the

2

shaft. In order to keep the view holder in proper alinement, I have provided with the clamp an alining means, which guides and holds the view holder in proper alinement with the shaft. This guide F may be stamped out of the same kind of metal from which the clamp is made and consists of a flat disk F' having a strip F² upturned at right angles thereto. When this guide is in position, the upturned strip rests in the enlargement of the cut-out part of the cross-bar, and the disk thereof is between the clamp and the under surface of the cross-bar. This disk portion is provided with a hole f which registers with the hole e, and through which a nail or screw which fastens the clamp to the cross-bar passes. The upturned portion F² is curved, the ends resting against the edge of the shaft and the middle portion resting against the shoulder of the cut-away portion of the cross-bar. This construction firmly holds the cross-bar and shaft in engagement laterally, and prevents any lateral play. Instead of making this guide separate from the clamp, I may stamp it out with the clamp, forming the guide integral with the end of the main part E' of the clamp, as shown in Fig. 6, and instead of providing the clamp with only one guide as shown in Figs. 3 and 30, I may form a guide on each end of the main portion E' of the clamp, as shown in Fig. 6 of the drawing. I may also use only the curved strip F² and tack it in the slot of the cross-bar between the cut-away portion 35 of the cross-bar and the shaft. This forms a convenient and simple spring guide to hold the cross-bar and shaft in alinement.

In Fig. 9 I have shown a modified construction of guide. In this construction instead of providing the clamp with a guide placed between the shaft and the shoulder of the cut-away portion of the cross-bar, I form at the ends of the leaf springs e², a cross strip e³ and upturn the ends thereof to form guide fingers e⁴. These guide fingers rest against the edges of the shaft at four points. The distance between the inner surfaces of each pair of these guide fingers is just the width of the shaft. As they bear upon both sides of the shaft on opposite sides of the cross-bar, they will securely hold the cross-bar in axial alinement with the shaft, and prevent any lateral movement between the shaft and the said cross-bar, as is apparent.

55 As many changes could be made in the above construction and many apparently widely different embodiments of my invention could be made without departing from the scope thereof, I intend that all matter contained in the above description or shown in the accompanying drawing shall be interpreted as illustrative, and not in a limiting sense.

I desire it also to be understood that the language used in the following claims is in-

tended to cover all of the generic and specific features of the invention herein described and all statements of the scope of the invention, which, as a matter of language, might be said to fall therebetween.

Having now described my invention, what I claim as new and desire to secure by Letters Patent is:

1. A clamp consisting of a main member, clamping means connected thereto and finger members extending directly from the main member, said main member being so constructed as to permit the clamping means to be moved when the finger members are moved toward each other.

2. A clamp consisting of a main member, clamping means connected thereto and finger members extending therefrom, a part of the main member being weakened so as to permit the clamping means to be moved when the finger members are moved toward each other.

3. A clamp consisting of a main member, clamping members connected thereto, and finger members extending therefrom, said main member being longitudinally slotted to permit the clamping member to be moved when the finger members are moved toward each other.

4. In a stereoscope, a shaft, a cross-bar slidably connected thereto, a clamp secured to the cross-bar, said clamp consisting of a main member, leaf springs extending at right angles from said main member and bearing upon the shaft, and finger pieces connected to the main member, said main member being weakened longitudinally to permit the leaf springs to be raised out of contact with the shaft when the finger members are moved toward each other.

5. In a stereoscope, a shaft, a cross-bar slidably connected thereto, a main member of a clamp secured to the cross-bar, leaf springs extending from said main member and bearing upon the shaft, and finger pieces connected to said main member, said main member being slotted longitudinally to permit the leaf springs to be moved out of contact with the shaft when the finger pieces are moved toward each other.

6. In a stereoscope, a shaft, a cross-bar slidably mounted thereon, a main member of a clamp secured to the cross-bar, leaf springs extending from said member and bearing upon the shaft, finger pieces connected to the main member, said main member being constructed to permit the leaf springs to be withdrawn from contact with the shaft when the finger pieces are moved together, and a guide connected to the clamp to hold the cross-bar in alinement with the shaft.

7. In a stereoscope, a shaft, a cross-bar provided with a slot on the under side thereof into which the shaft fits, said bar being

slidably mounted on the shaft, a clamp having a main member spanning said slot and secured to the cross-bar, leaf springs integral with said member and bearing on the shaft, 5 finger pieces integral with the main member, said main member being provided with a slot longitudinally thereof so that the leaf springs may be raised from the shaft when the finger pieces are moved toward each other, a guide 10 secured to the cross-bar, said guide having an upturned member seated in the slot between

the edge of the shaft and the shoulder of the slot.

In witness whereof I have hereunto set my hand at New York in the county of New York and State of New York, this 27th day of March, 1906.

HENRY E. RICHMOND.

In presence of—

T. R. RICHARDS,
H. J. LILLIE.
